UNITED STATES PATENT OFFICE.

HERMAN GOTTESMAN, OF NEW YORK, N. Y.

LOCK-OPERATED CIRCUIT-CLOSER.

1,307,628.

Specification of Letters Patent. Patented June 24, 1919.

Application filed February 17, 1919. Serial No. 277,407.

To all whom it may concern:

Be it known that I, HERMAN GOTTESMAN, a citizen of Austria, residing at New York city, county and State of New York, have 5 invented certain new and useful Improvements in Lock-Operated Circuit-Closers, of which the following is a full, clear, and exact description.

This invention relates to improvements in 10 locks for doors or other closures, one of the objects of my invention being to provide an alarm system for locks that will indicate or sound an alarm whenever anyone tampers with the lock in an attempt to open the door 15 or closure equipped with my improved lock. In the present embodiment of my invention, I employ an electric alarm system, the circuit of which includes certain elements of the lock, said elements being arranged to 20 close the circuit should anyone attempt to set the combination and turn the knob which operates the tongue or bolt for the door or closure.

I will now proceed to describe my invention 25 in detail, reference being had to the accompanying drawing, forming part hereof, wherein:

Figure 1 is a plan view of an embodiment of my invention, the cover being removed;

30 Fig. 2 is a longitudinal sectional view of the greater part of the lock, the section being taken on a line 2—2 in Fig. 1;

Fig. 3 is an enlarged diagrammatic plan view of a portion of the lock;

35 Fig. 4 is an enlarged fragmentary plan view, illustrating the hands to select the combination; and

Fig. 5 is a diagrammatic face view illustrating a door or closure.

40 As herein arranged, my improved lock consists of a casing 6 having at one end a slidably mounted tongue or bolt 7 to engage the hasp in a door frame or the like, said hasp and door-frame being omitted. The 45 tongue or bolt 7 is operated by means of a bar 6^a which in turn is operated by a cam 7^a carried by a shaft 8 operable by means of a knob 9, the knob being located exteriorly of the door or closure, as indicated in Fig. 5.

50 Within the casing 6, I place a train of intermeshing gears 10, 11, 12, 13 and 14. The gear 11 is mounted on a tubular shaft 15 within which a shaft 16 is located carrying gear 12. The tubular shaft 15 also carries an hour-hand 17 and the shaft 16 a minute-hand 18.

As herein arranged, the mechanism is set so that the bolt or tongue 7 can be moved out of engagement with its coöperating keeper (not shown), by setting hands 17 and 18 to a certain time. While I have indicated a dial 19 having time indications, letters or numerals could be used. When the hands 17 and 18 are moved, by rotating shaft 16 by means of the knob 20 to open the door or closure, a certain element of the lock is placed in condition to permit of the operation of the bar 6^a to move the tongue or bolt 7. To operate bar 6^a, I provide the cam 7^a which is operable in the direction of the arrow 21 by means of shaft 8 and knob 9.

To control the movement of bar 6^a to open position, I provide a disk or rotatable stop 22 having serrations 23 (see Fig. 3), and a slot 24 (a gear may serve for this purpose), arranged to receive a tongue 25 carried by bar 6^a when said slot is brought into alignment with the tongue 25. The disk 22 will be secured to gear 14 and rotate with it. The proportion of the gearing will be preferably twelve to one; hence one revolution of the tubular shaft 15 will require twelve revolutions of shaft 16. Whenever hands 17 and 18 are moved to indicate half past five (in this instance), the slot 24 in disk 22 will 80 align with the tongue 25. At such a time the bar 6^a can be moved to move tongue 7 to open the door or closure. To change the combination, the hand 18 will be removed from the squared end 26 of shaft 16 and replaced in a different position on the shaft. In this instance, the shaft 16 is arranged for 85 four different combinations. Should the end of shaft 16 be hexagonal, six combinations would be provided for. The four combinations herein referred to, could be five-thirty, six-thirty, seven-thirty or eight-thirty. These combinations are merely illustrative.

At any time, other than when slot 24 and tongue 25 are caused to align, the tongue 25 would strike the disk 22 and engage one of the serrations 23. The engagement of the serrations, by said tongue, would prevent the operation of the hands 17 and 18 because the train of gears would be locked. Furthermore, when tongue 25 contacts with disk 22, a circuit for a bell 26 (in this instance), would be completed and said bell 100 would ring.

To form a circuit including bar 6^a and disk 22, I mount said disk upon a conductor 27 connected by a wire 28 to one side of a

- battery 29. The opposite side of the battery is connected by a wire 30 to bell 26, the bell 26 being connected to a contact 32, in the casing 6, by a wire 31. The contact 32 bears 5 against the bar 6^a. It will be apparent that the bell will ring whenever bar 6^a is moved to the right, in Fig. 1, unless the proper combination is set, because tongue 6^a will strike the disk 22, and complete the circuit.
- 10 Should the bar 6^a be moved, by manipulating knob 9, the bell would ring, giving notice that the lock was being tampered with, but the door could not be opened, as such movement would not be sufficient to move tongue 15 7 to clear its keeper.

When tongue 25 is moved into the slot 24 in disk 22 after the proper combination has been set, the bell will not ring because tongue 25 will not touch the disk 22 as the slot 24 20 will be large enough to receive the tongue without said tongue touching same; hence the alarm circuit will not close.

Having now described my invention, what I claim is:—

- 25 1. In a lock operated circuit-closer, a locking tongue or bolt, a bar to operate same, means to operate said bar, a rotary stop adjacent the bar having a slot therein, a tongue carried by the bar to enter said slot when 30 the rotary stop is rotated to cause the slot and tongue on said bar to aline, means to rotate said stop, and means carried by the stop to coact with the tongue on the tongue-

operating bar to prevent rotation of the stop when the tongue on the bar and slot in the 35 rotary stop are out of alinement.

2. In a lock operated circuit-closer, a train of intermeshing gears, means to rotate said gears a predetermined amount, a rotary disk, having a slot, operated by said gears, said disk forming one terminal, a locking-bolt, a bar, constituting the other terminal, to operate the bolt, means to operate the bar, a projection carried by the bar to enter the slot in said disk when said disk is rotated to cause the slot therein to be moved to a predetermined position and to contact with said disk to complete the circuit should the bar be moved at a time when the slot in said disk is out of alinement with the projection 50 on said bar, and means to prevent the rotation of the disk when the projection on the tongue-operating bar contacts with said disk.

3. The combination of elements recited in 55 claim 9, with the additional feature of serrations carried by the disk to engage the projection on the tongue-operating-bar when the projection is moved to contact with said disk.

Signed at New York city, N. Y., this 11 day of February, 1919.

HERMAN GOTTESMAN.
